UNITED STATES PATENT OFFICE.

ALBERT N. SHELDON, OF VENTURA, CALIFORNIA.

APPARATUS FOR WALKING ON WATER.

Application filed December 13, 1927. Serial No. 239,635.

This invention relates to an apparatus that enables a person to walk on water, being an improvement over the disclosure in my former Patent No. 1,475,031, dated November 5, 20, 1923.

An object, in general, is to improve the operation of the apparatus disclosed in said former patent.

More particularly, an object of the invention is to make provision for positive operation, by the walker, of the paddles or fins, thereby to obtain quicker movement of said fins from collapsed into open position for holding of the float against rearward motion, as much as possible.

Other objects and advantages will appear in the subjoined detailed description.

The accompanying drawings illustrate the invention:

20 Figure 1 is a plan view of an apparatus constructed in accordance with the provisions of this invention, solid lines indicating the parts in the mid-stride position, and broken lines indicating the frame and one of the 25 floats in the positions they assume at the end of a stride.

Figure 2 is a side elevation of Figure 1 partly in section.

30 Figure 3 is a sectional elevation on the line indicated by 3—3, Figure 2, the upper portion of the steering column and the steering handle being broken away to contract the view.

35 Figure 4 is an enlarged sectional detail on the line indicated by 4—4, Figure 2.

Figure 5 is a sectional elevation on the line indicated by 5—5, Figure 4.

40 Figure 6 is an enlarged fragmental longitudinal section on the line indicated by 6—6, Figure 1. The paddles or fins are shown in open position.

Figure 7 is a view similar to Figure 6 with the paddles or fins in closed position.

45 There is provided a suitable frame indicated in general by the character 10 and constructed, in this instance, of longitudinally extending lower inner members 12 and longitudinally extending upper inner members 13. The members 11 converge at their ends and 50 are there connected with the members 12. The members 13 have downwardly bent portions 14 at their front ends connected to each other by a cross member 15. The rear ends of the members 11 are connected by a cross 55 member 16 and the rear ends of the members

13 are connected by a cross member 17. At intervals the members 11, 12 and 13 are connected by transversely extending trusses 18. Preferably the frame 10 is principally constructed of seamless steel tubing with the different members welded to one another.

Positioned beneath the frame is a pair of spaced floats 19 extending parallel with one another and decked over, the decks being indicated at 20. The decks 20 are provided with openings 21 through which the operator passes his feet. In the instance shown in the drawings the floats 19 are divided into a number of water tight compartments 23, 24 so as to insure buoyancy and any water that 70 may accidentally enter the openings 21 will not be able to penetrate into any of said water tight compartments and swamp the apparatus.

75 The members 11, 12 serve as guides and are engaged by bearings 25 each of which is constructed as follows: A suitable standard 26 is fastened by screws 27 to the deck of the float and it supports three pins 28. On the pins 28 are journaled grooved rollers 29, the pins 28 being positioned to bring the peripheries of the rollers in radial relation to the guides which they engage. The radius of curvature of the peripheries of the rollers, transversely thereof, is slightly greater than the radius of curvature of the guides so as to prevent any tendency to binding between the rollers and the guides. In this particular instance six bearings 25 are provided, one on each of the floats near the outer edge thereof engaging the adjacent members 11, and two on each of the floats near the inner edge thereof engaging the adjacent member 12.

85 In order that the frame may be positively advanced half the distance that either of the floats is advanced relative to the other float, the following construction is provided. Pivoted at 30 at its center to a transverse member 31, supported by the members 12, is a lever 32 and pivoted to the outer ends of said lever at 33 are links 34. The rear ends of the links 34 are pivoted at 35 to the decks, respectively, of the floats, preferably along the longitudinal axes of said floats, though such position is not essential. It will now be seen that advancing of either of the floats will swing the lever 32 about one of the pivots 33 acting as a fulcrum, said fulcrum shifting, however, so as to permit the pivot 30 to advance in a straight path. Since the pivot 30 is midway 100

105

110

of the distance between the pivots 33, the frame will be advanced just half of the distance traversed by the float.

Fixed to the cross members 16, 17 is a vertical bearing 36 for a rudder post 37. The rudder post 37 is provided with an arm 38 which carries a rudder 41.

A triangular steering arm 43 is connected at its ends to the rudder. To the opposite 10 sides of the arm 43 are secured cables 45 which are crossed and extend forwardly and are secured to the opposite ends of the arms 46 projecting from the opposite sides of a steering shaft 47 having a steering handle 48 at 15 its upper end. The shaft 47 is journaled in a steering column 49 connected by cross members 50 to the frame members 12, 13. Turning of the handle 48 in either direction effects steering of the apparatus in that direction.

20 If desired, and it is preferable, the frame may be provided between the floats with a center board 55.

The construction above described is the same as that described in the hereinbefore 25 mentioned patent and the novel features of the invention are described as follows:

Pivoted horizontally at 56 by a hinge or any other suitable means are paddles or fins 57. As many fins as desired may be employed, 30 there being shown in this particular instance, three for each float, one near each end of each float and one about the middle of each float. Suitable mechanism is provided for operating the fins 57 into extended or open 35 position and into collapsed position, there being one set of mechanism for operating the fins of each float. Since the fin operating mechanisms are the same, only one will be described herein. Connected with each of the

40 fins 57 is an arm 58. The arms 58 extend along one side of the float with which the fins 57 are associated and each arm 58 is pivoted at 59 to a connecting rod 60 which is also positioned outside of the float and longitudinally 45 thereof. A coil spring 61, connecting the rod 60 to one end of the float, functions to hold and return the rod 60 in its forward position with the fins collapsed, as in Figure 7. Pivoted at 62 to the rod 60 is a link 63 which, in turn, is pivoted at 64 to a lever arm 65 on a shaft 66 which turns in bearings 67 positioned in opposite sides of the float. The link 63 and lever arm 65 are disposed outside of the float and the shaft 66 extends into and 55 across the float. The shaft 66 is provided inside of the float with another lever arm 67 which is pivoted at 68 to a link 69 that, in turn, is pivoted at 70 to a foot actuated lever 71. The fulcrum 72 of the lever 71 is supported 60 on the bottom of the float. In this particular instance, the lever 71 is approximately U-shaped, the cross member thereof being provided with a rounded member 73 upon which the foot of the operator is adapted to rest 65 when his weight is thrown on that foot. The

member 73 is adapted to lie beneath the arch of the foot directly in front of the heel. When the operator bears his weight on the lever 71, the parts will be moved into and held in the positions shown in Figure 6, with the fins 70 extended. When his weight is taken off of the lever 71, the parts will assume the positions shown in Figure 7 so that the fins will be collapsed.

The invention operates as follows: The 75 pedestrian standing with one of his feet in each of the floats with his weight resting equally on each foot will progress on the water by shifting of his weight largely on one foot and shoving his other foot forwardly so as to advance the float attached to the latter foot. The weight being off of his forwardly pressed foot, will permit the spring to effect retraction of the fins to the collapsed position shown in Fig. 7. The ball of this 80 foot will rest on the bottom of the float and will be prevented from slipping forward on said bottom by reason of the heel of said foot pushing against the member 73. The fins of the forwardly moving float being collapsed rearwardly permit of free forward motion of said float over the water, whereas the fins of the float that support the weight of the pedestrian hold the second float against any substantial rearward motion. The moving float, 85 through the lever and links 32, 34, pushes the frame forwardly. When this stride is completed, the operator will shift his weight, thus extending the fins that were formerly collapsed and collapsing the fins that were formerly extended and then a step or stride will be taken by that foot from which the weight has been relieved.

I claim:

1. An apparatus for walking on water comprising floats, a fin movably mounted on each of the floats, a lever mounted in each of the floats operable in one direction by weight of the operator imposed thereon, and a means connected with each fin operable by movement of each of the levers in said direction to move the associated fin into extended position. 105

2. An apparatus for walking on water comprising floats, a fin movably mounted on each of the floats, and a mechanism connected with each fin operable by weight of the operator imposed thereon to effect movement of the associated fin into extended position. 115

3. An apparatus for walking on water comprising floats, a fin movably mounted on each of the floats, and a mechanism connected with each of the fins operable by the foot of the operator as he shifts his weight from one float to the other to effect movement of the associated fin. 120

4. An apparatus for walking on water comprising a frame, parallel floats beneath the frame, means shiftably supporting the frame on the floats, a fin movably mounted on each of the floats, a means whereby longitudinal 130

movement of either float with respect to the frame advances said frame, and a means operable by weight of the operator imposed thereon to positively actuate each fin into extended position.

5. An apparatus for walking on water comprising a frame, parallel floats beneath the frame, means shiftably supporting the frame on the floats, a lever pivoted near its middle 10 to the frame, links pivoted to the ends of the lever and to the floats respectively, a fin movably mounted on each of the floats, and a mechanism connected with each fin operable by the weight of an operator imposed thereon 15 and supported by the floats to move the associated fin from one position to another.

6. An apparatus for walking on water comprising floats, a means shiftably connecting the floats, a fin movably mounted on each of

the floats, and a mechanism connected with each fin operable by the weight of an operator imposed thereon and supported by the floats to move the associated fin from one position to another.

7. An apparatus for walking on water comprising floats, a frame shiftably connecting the floats, a means operable by advancing either of the floats to advance the frame relative to the other float, a fin movably mounted on each of the floats, and a mechanism connected with each fin operable by the weight of an operator imposed thereon and supported by the floats to move the associated fin from one position to another.

Signed at Los Angeles, Calif., this 28 day 35 of Nov., 1927.

ALBERT N. SHELDON.
